UNITED STATES PATENT OFFICE

2,529,167

LEAKPROOF OIL FILTER

Felix Lewis and James Shuler, Savannah, Ga.

Application April 26, 1946, Serial No. 665,154

1 Claim. (Cl. 210—183)

1

This invention relates to a leak proof oil filter for internal combustion engines or other types of engines wherein an oil filter is incorporated in the lubricating system.

An object of the invention is to provide a filter which will prevent the loss of oil due to the failure of the sealing gasket and the resultant damage to the engine due to the failure of the gasket.

Another object of the invention is to provide a filter having a reservoir which will maintain lubrication of the engine should the filter fail to properly function.

With the above and other objects and advantages in view the invention consists of the novel details of construction, arrangement and combination of parts more fully hereinafter described, claimed and illustrated in the accompanying drawing in which:

Figure 1 is an elevational view partly in section and partly broken away of an embodiment of the invention.

Figure 2 is a modified form thereof and

Figure 3 is a detailed fragmentary view of a modified form of connection for the filter.

Referring more in detail to the drawings the reference numeral 10 designates the filter embodying the invention which comprises the housing shell or main oil container 12, having formed integral therewith adjacent the top edge thereof the circular portion 14 forming an annular oil reservoir. The shell 12 is formed with a concave bottom 16 having the center flat circular portion 18 on which is positioned a washer 20 and the filter cartridge 22 is seated on the washer and the concave bottom maintains the filter cartridge out of contact with the bottom of the container. The formation of the bottom also increases the rigidity of the bottom 16.

The portion 18 at the center thereof is provided with an opening 24 to receive the main drainage pipe 26 which is welded to the portion 18 at 28 to maintain the pipe in position in the container at the center thereof. The cartridge 22 being of the conventional type is provided with a vertical bore 30 for the reception of the pipe 26. The pipe 26 for a major portion thereof within the container 12 is provided with perforations 32 for the passage of filtered oil therethrough and a partition 34 at the top thereof closes the pipe 26 and the portion above the partition 34 is internally threaded at 36 to receive the bolt 38.

The bolt 38 retains the removable cover 40 on the container. The cover 40 is formed with the

convex portion 42 which closes the container 12 and the flat ring portion 44 which covers the circular portion 14 and the portion 44 is provided with an outer depending marginal flange 46 and an inner circular shoulder 48 which engages the inner marginal edge of the container 12 and a ring gasket 50 is placed in engagement with the inner face of the portion 44 intermediate to the flange 46 and shoulder 48 to form an oil tight seal between the cover container and the beads 51 of the reservoir on which the gasket is seated.

The head of the bolt 38 engages a washer 52 resting on the circular flat portion 54 of the cover 40 and a tapered coil spring 56 engaging the top of the cartridge 22 and the inner face of the portion 54 will when the bolt is tightened to seal the cover and container hold the cartridge in position. The pipe 26 at the lower end thereof is provided with a T-head 58 for connection to the outlet pipe 60 to the engine not shown and with the circular portion 14 by pipe 62 and coupling 64 on the outlet 66 secured to the bottom of the circular portion 14 by welding 68 or the like. The container at the center thereof is provided with an inlet 70 which by means of the elbow 72 is connected to the outlet of the engine.

Should the gasket 50 fail oil would not leak out of the container but would enter circular portion 14 and return to the engine by means of the pipe 62 which is connected to the T-head 58 which, in turn, is connected to the outlet pipe 60 to the engine thus preventing the engine from being damaged from loss of oil.

In Figure 2 the filter 10 comprises the housing shell 12 and circular portion 14 but a partition 74 is formed adjacent the bottom of the shell and the pipe 26 is welded thereto at 76 in the opening 78 and a convex washer 80 supports the filter cartridge 22 thereon.

The bottom 82 of the housing 12 is convexed to form the vacuum chamber 84 which is provided with an elbow 86 seated in the central opening 88 and welded thereto at 90 and pipe 60 connects the shell to the engine.

Immediately below the partition 74 an elbow 92 is seated in the opening 94 and secured to the housing by welding 96 and the elbow 92 is connected by a pipe 62 to the outlet 66 of the circular portion 14 as previously described.

In this instance two ring gaskets 98 and 100 are positioned intermediate the flange 46 and shoulder 48 and a depending triangular annular projection 102 spaces the gaskets so that they are properly seated on the beads 51 of the circular portion,

The operation of this form is as previously described the oil returning to the chamber 84 from the circular portion 14 and thence back to the engine.

In Figure 3 there is shown a modified form of the invention shown in Figure 2, wherein the bottom 82 of the housing 12 has a T coupling 104 secured to the opening 88 therein by welding 90. The pipes 60 and 62 are connected to the coupling 104, in the manner shown, so that the oil in the chamber 84 will not back up into the reservoir 14.

Thus a leak proof filter has been provided that will accomplish the objects of the invention and it is believed that the operation and construction of the filter will be apparent to those skilled in the art.

It is also to be understood that changes in the minor details of construction may be resorted to provided they fall within the spirit of the invention and the scope of the appended claim.

Having thus described the invention, what is claimed as new and desired to be secured by Letters Patent is:

A filter, comprising a shell having a concave bottom, a raised apertured circular portion centrally of the bottom, a washer on said portion, a drainage pipe having a plurality of perforations therein passing through the apertured circular portion and fixed to the shell outwardly of the bottom thereof, an oil filter element over the drainage pipe within the shell, and engaging the circular portion in the bottom thereof, an annular circular portion formed on said shell adja-

cent the open top thereof, a removable cover for said shell and said annular circular portion, means engaging the upper rims of said shell and said annular circular portion and said cover for sealing the said shell and annular circular portion, a partition in the pipe, threads in said pipe above said partition, a bolt passing through said cover to engage the threads of said pipe to retain said cover in place, a spring interposed between said cover and said filter element and about said bolt and the upper end of said pipe to retain said filter element fixed in said shell, a T-shaped head on the lower end of said drainage pipe, an overflow pipe connecting the annular circular portion with the T-head on the drainage pipe and means for connecting the shell to an outlet pipe from the oil system of the engine.
